CLAIM

The ornamental design for the transparent drinking vessel, as shown and described.

DESCRIPTION

FIG. 1 is an isometric view of transparent drinking vessel; FIG. 2 is front elevation view of the transparent drinking vessel shown in FIG. 1;

FIG. 3 is a top plan view of the transparent drinking vessel shown in FIG. 1; and,

FIG. 4 is a bottom plan view of the transparent drinking vessel shown in FIG. 1.

The broken lines in the drawing depict portions of the transparent drinking vessel that form no part of the claimed design.
